(57) **CLAIM**

The ornamental design for a metal shade, as shown and described.

DESCRIPTION

This application is related to commonly assigned, co-pending design patent application Ser. No. 29/713,450, filed on Nov. 15, 2019 by Klinker et al. and entitled "Metal Shade", and is related to commonly assigned, co-pending design patent application Ser. No. 29/713,454, filed on Nov. 15, 2019 by Klinker et al. and entitled "Metal Shade", which applications are hereby incorporated herein by reference in their entirety.

FIG. 1 is a top perspective view of a metal shade in accordance with the new design;

FIG. 2 is a bottom perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof; and,

FIG. 8 is a bottom view thereof.

The broken lines in the drawings illustrate portions of the metal shade which form no part of the claimed design.

1 Claim, 8 Drawing Sheets
